UNITED STATES PATENT OFFICE.

TIMOTHY T. OVERSHINER, OF CHILlicothe, OHIO, ASSIGNOR OF ONE-HALF
TO P. S. LEWIS, OF MASON COUNTY, WEST VIRGINIA.

NUT-LOCK.

SPECIFICATION forming part of Letters Patent No. 247,101, dated September 18, 1881.

Application filed July 8, 1881. (No model.)

To all whom it may concern:

Be it known that I, TIMOTHY T. OVERSHINER, of Chillicothe, in the county of Ross and State of Ohio, have invented certain new and useful 5 Improvements in Nut-Locks; and I do hereby declare the following to be a full, clear, and exact description of the invention, such as will enable others skilled in the art to which it pertains to make and use it, reference being had to 10 the accompanying drawings, which form part of this specification.

My invention relates to an improvement in nut-locks; and it consists in making in the inner surface of the nut, from each edge, a 15 tapering recess, into one or more of which recesses is slipped a small steel sharp-pointed locking device, which, when an attempt is made to turn the nut backward, catches in or against the surface of the piece against which the nut 20 bears, and thus locks the nut in place, as will be more fully described hereinafter.

The object of my invention is to devise a cheap, simple, and efficient lock for nuts, which will prevent them from becoming loose, and 25 which can be readily and easily applied and removed.

Figure 1 is a vertical section of my invention, taken through the nut and the locking device. Fig. 2 is a perspective of the nut, taken 30 from the inner side. Fig. 3 is a perspective of the locking device by itself.

A represents an ordinary screw-threaded bolt, and B a common nut applied thereto. Made in the surface of this nut, on its inner side, 35 are a number of tapering recesses, C, which run parallel with one of the sides of the nut, and which are deepest at their outer ends. There may be any desired number of these recesses made, but one from each side will be 40 found to answer every purpose. After the nut has been screwed tightly into position the locking device F, which is constructed as shown,

is slipped into any desired one of the recesses and forced sufficiently tightly in place by being struck by some instrument to prevent it from 45 readily coming out. This causes the sharp point of the device to catch in the surface against which the nut bears, and whenever it is attempted to turn the nut backward the incline formed on the recess causes the locking device 50 to sink deeper into the surface, and thus effectually prevents the nut from being turned around.

When it is desired to unlock the nut it is only necessary to turn it a very little forward, which 55 makes room enough in the recess in which the locking device is placed for it to be raised slightly outward, and thus loosen it from the surface against which it is locked.

The great advantage of a very small locking 60 device like the one here shown consists in the fact that it is hidden from the eye, so as not to mar the appearance of the work. It can be applied to nuts of all kinds where but a small piece has been cut out from its under side by 65 any suitable tool, and is so cheap as to cost almost nothing.

Having thus described my invention, I claim—

In a nut-lock, the combination of a nut having one or more inclined recesses made in its inner side, which recesses are deepest at their outer ends, with a locking device, F, which has a sharp edge formed on its inner surface, whereby when the nut is turned backward the sharp 70 edge is forced into the surface against which the nut bears, substantially as shown and described.

In testimony whereof I affix my signature in presence of two witnesses.

TIMOTHY TAYLOR OVERSHINER.
